UNITED STATES PATENT OFFICE.

HIRAM C. BRADEEN AND SAMUEL BRIGGS, OF MCKEESPORT, PA.

SKELP-HEATING FURNACE.

SPECIFICATION forming part of Letters Patent No. 269,380, dated December 19, 1882.

Application filed February 6, 1882. (No model.)

To all whom it may concern:

Be it known that we, HIRAM C. BRADEEN and SAMUEL BRIGGS, both of McKeesport, in the county of Allegheny and State of Pennsylvania, have invented a new and useful Improvement in Skelp-Heating Furnaces; and we do hereby declare the following to be a full, clear, and exact description thereof.

Our invention relates to the construction of skelp-heating furnaces; and it is designed to obviate a difficulty heretofore experienced, which consists in the unequal heating of the skelps therein. As heretofore constructed, the air and gas have been thrown into the furnace from a single combining-flue, and as the furnace is long, necessarily, for the purpose of taking in the long skelp, the tendency of the draft and pressure has been to carry the heat from the flues to the farthest end of the furnace and over the front end of the skelp without properly heating it at that place. The result of this unequal temperature of the furnace is that the skelp is often burned in one part and imperfectly heated in another, which produces great loss in the operation of the furnace.

Our invention consists mainly in the use of a distributing and equalizing chamber which serves to reduce the pressure of the gas, provided with a series of flues which lead to the regenerator at various points, so as to equalize the distribution of the gas.

It also consists in certain details of construction which will hereinafter more fully appear.

To enable others skilled in the art to make and use our invention, we will now describe the same by reference to the accompanying drawings, in which—

Figure 1 is a vertical cross-section of the furnace and its regenerators on the line I K of Fig. 3. Fig. 2 is a longitudinal section on the line E F G H of Fig. 1. Fig. 3 is a longitudinal vertical section on the line A B C D of Fig. 1. Fig. 4 is a plan view of the regenerator-flue valves, and Figs. 5 and 6 are vertical sectional views of the same with the valves in reverse positions.

The bed *a* of the furnace is long and narrow, as shown in Figs. 1 and 3. Beneath it are the regenerators *b b' c c'*, the regenerators *b b'* being for the air and the regenerators *c c'* being for the gas. The flues leading to the bed *a* of the furnace are shown at *d d'* and *e e'*.

Arranged centrally between the regenerators *c c'* is a central gas-distributing chamber, *f*, from the bottom of which, leading downward to the lateral flues *h h'*, are drop-flues *g g'*, said flues *g g'* being controlled by sliding valves *i i'*, working on the bottom of the chamber *f* by means of rods *i''*. The gas is supplied to the chamber *f* by a pipe or conductor, *k*, and passes thence down through the ports *g* or *g'*, and by lateral flues *h* or *h'* under the walls *l l* into the regenerator *c* or *c'*. There are one or more of the passages *g h* leading from the chamber *f* to each regenerator, which passages, being arranged at suitable intervals under the entire length of the furnace, cause the gas to be supplied by the regenerator in such a manner that it shall pass thence up through the flues *e e'* and be distributed equally to all parts of the bed. The air-flues *d d'* run up from the regenerators *b b'* back of the flues *e e'*, so as to cause the air to be commingled with the gas at its entrance into the bed.

As heretofore constructed, the regenerator-flues which lead to the stack-flue *o* have been of reduced cross-sectional area and made with abrupt curves or angles where they run into the stack-flue. This impedes the draft and causes the regenerator to become foul and choke. I cure the defect by running the flues *m m' n n'* together by converging lines leading directly from the regenerator, substantially preserving the same cross-sectional area throughout, thus avoiding abrupt angles or curves, which would impede the draft or cause the fouling of the flues. Each of the flues *m m' n n'* is controlled by a separate valve, *p p' q q'*. The valves of each pair of flues (there being one on each side) are mounted upon a single shaft, *r*. The air-flue is larger than the gas-flue, and the valve of the air-flue is consequently larger than the valve of the gas-flue. The valves *p p' q q'* are simple flaps or doors, mounted on the shafts *r*, so as to turn therewith. Attached to the larger valve *p* or *p'* of each shaft is a rod, *s*, by which it may be opened or closed. The air-supply opening *t* is above the valve, so that when the valve is drawn up to open the flue for the passage of the waste gases to the stack-flue *o* it will close the air-opening *t*. As the air and gas valves are on the same shaft, the closing of the air-opening *t* and opening of the air-flue to the stack also opens the

gas-flue to the stack. When the air-supply *t* is open the gas-flue valve *n* or *n'* must be closed as the gas is entering through chamber *f*; but when the waste heat is going out it passes through both air and gas flues on that side. Consequently the valves must both be open for exit and only the air-flue for inlet purposes. This construction has its necessity and value from the fact that the gas is supplied to

10 the regenerators by an independent chamber, flue, or pipe, and not by means of the flues *n* *n'*.

To prevent the valves from leaking, we form in the bottom of the flue, where they strike it, a lateral recess, *u*, which is filled with clay or 15 luting, so that when the edge of the valve comes down to place it will bury itself therein and close the joint tightly. By this means we are able to close the flues tightly, and to obtain a more perfect control of the draft and operation of the furnace.

20 What we claim as our invention, and desire to secure by Letters Patent, is—

1. A skelp-heating or similar furnace having, in combination with the gas-regenerators, 25 a gas distributing and equalizing chamber provided with a series of flues controlled by valves leading into the gas-regenerators at different points along and under the entire length of the bed, substantially as and for the purposes described.

2. The combination, in a skelp-heating furnace, of a gas-distributing chamber, a regenerator, a series of gas-flues leading from the distributing-chamber to the regenerator, a furnace-hearth, and a series of gas-flues leading 35 from the regenerator to the hearth, substantially as and for the purpose specified.

3. The combination, in a regenerator-furnace, of a gas-distributing chamber having a valved flue or flues leading to the gas-regenerator, and exit-flues leading from the air and gas regenerators to the stack, each provided with a valve, the valves of the same side being arranged on and actuated by a stem or shaft common to both valves, substantially as 40 and for the purpose specified.

4. In a regenerator, the combination of a flap-valve with a flue having a recessed bottom for the reception of luting material, substantially as and for the purpose specified.

50 In testimony whereof we have hereunto set our hands this 24th day of January, A. D. 1882.

HIRAM C. BRADEEN,
SAMUEL BRIGGS.
